OPHTHALMIC MOUNTING

James A. Sweeney, Providence, R. I., assignor to
Universal Optical Corporation, a corporation of
Rhode Island

Application December 16, 1932, Serial No. 647,613

4 Claims. (Cl. 88—47)

This invention relates to an ophthalmic mounting, more particularly the mounting of a clamp or so-called strap upon a lens and has for one of its objects the provision of a construction which will apply sufficient pressure upon the retaining screw or bolt for securing the strap to the lens and prevent the bolt or screw from becoming accidentally loosened.

Another object of the invention is to provide a mounting which may be secured to a lens without an accurate location of the hole thru the lens thru which the retaining screw passes.

Another object of the invention is the provision of a unit assembly by which the strap may be mounted upon the lens by a single screw and be self-conforming and flexibly maintained in the desired alignment with the lens.

A further object of the invention is the provision of a unit assembly by which shocks or jars may be absorbed and the spring may be forced beyond the edges of the body of the strap and maintain greater pressure upon the securing bolt or allow great flexible pivotal movement of the strap and lens.

A still further object of the invention is the provision of a unit assembly by which the spring may be maintained in its desired position against rotation.

With these and other objects in view, the invention consists of certain novel features of construction, as will be more fully described, and particularly pointed out in the appended claims.

In the accompanying drawing:

Fig. 1 is a front elevation of a spectacle showing the improved straps as mounted thereon.

Fig. 2 is an enlarged view of a fragmental portion of the lens, strap and bridge with portions in section to better illustrate the relative arrangement of the parts.

Fig. 3 is a view similar to Fig. 2 with the parts in full;

Fig. 4 is a perspective view of one form of strap detached from the lens;

Fig. 5 is a perspective view of a slightly modified form of strap detached from the lens;

Fig. 6 is a perspective view of the strap with one of the ears of the strap broken away and also exposing one type of pin;

Fig. 7 is a perspective view similar to Fig. 6 and showing a differently shaped pin as formed thereon;

Fig. 8 is a sectional view of a still further modified form of strap and showing an opening in, rather than a pin on, the body thereof;

Figs. 9, 10 and 11 are perspective views of

straps with variously shaped cooperating means for receiving differently shaped pins or projections;

Fig. 12 is a perspective view of a strap showing a projection formed thereon to fit within a recess such as illustrated in Fig. 8.

Referring to the drawing, numeral 15 designates the lenses to which there are attached straps designated generally 16 at the outer edges of the lenses and straps designated generally 17 at the inner edges of the lenses. Temples 18 are connected to the straps 16 while the bridge 19 is connected to the straps 17.

The type of strap here illustrated is used on a rimless mounting and consists generally of a body portion 20 with a pair of ears 21 secured to the body portion and extending therefrom. Each of these ears is pierced, the opening 22 in one ear being threaded while the opening 23 in the other ear is countersunk. A securing bolt 24 having a head shaped to fit within the countersunk portion extends thru the opening 23, thru a hole in the lens and into the threaded opening 22 in the other ear.

The body portion 20 of my strap is provided in each case with a flat, inner surface 25 which extends along the edge of the lens. The outer edge 26 of this strap may be flat and parallel to the edge 25, as illustrated in Figs. 1 to 4 inclusive, or it may be convex as at 27, to provide a greater area to which the arm of the bridge 19 may be secured for the support of the strap.

A leaf spring 28 is concavo-convex in shape and positioned with its convex surface against the lens side or inside the flat surface of the body portion of the strap while its end portions 29 engage the edge of the lens and maintain a pressure on the securing bolt 24 to prevent the bolt from becoming loosened and detached from its securing position. This spring also permits of flexibility between the lens and the strap by the swinging of the strap about the bolt 24 and in cases where the lens strap is of a length less than the length of the spring as shown at 30, in Fig. 3, the end portions 29 of the spring may be flexed to a distance beyond the plane of the inner flat surface 25 of the body and thus permit greater flexibility or swing of the lens about the bolt 24 as a pivot by reason of this shorter length. By this arrangement the spring or lens is maintained in its desired position relative to the bridge and the other lens altho allowing of flexibility of movement to absorb shocks and prevent breakage.

The spring is maintained in the desired position to exert even pressure on either side of the pivot 55

24 by reason of a projection on one part and a recess in the other.

My preferred form of centering means is to draw up a projection on the body part, which projection I have illustrated as elongated and of rectangular shape as at 31 in Fig. 4, while an opening 32 in the spring, shown in Fig. 10 is shaped to fit the same. In other instances, the projection 33 is drawn up in a square shape by 10 suitably striking the body portion in a die and I have illustrated in Fig. 9 a square opening 34 in the spring to fit the same. In another instance in Fig. 6, the projection 35 is of oblong or generally elliptical shape while an oblong or elliptical 15 opening 36 is indicated in Fig. 11 to fit the same. In Fig. 8, I have illustrated an opening 37 in the body part, while in Fig. 12 a correspondingly-shaped projection 38 is cut and raised from the stock of the spring to fit within this opening and 20 thus these interfitting parts may vary in detail but all serve to maintain the spring in its desired vertical position and also by reason of the shape of these interengaging parts the spring is prevented from rocking to any material extent relative to the strap that it may always maintain 25 engagement with the lens.

It will also be observed that the spring is positioned between the ears 21 and by this arrangement the spring is also prevented from undue 30 rocking. In some instances, I may rivet over the head of the pins formed as at 40, in Fig. 2, altho I do not wish to be confined to riveting the pin for securing it to the body portion of the strap as the same may be soldered or welded and struck 35 in suitable tools afterwards to restore the stiffness to the spring.

The arms of the bride 19 may be connected to the outer surface of the strap in any suitable manner such as by soldering, riveting or the like.

40 The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In an ophthalmic mounting, a lens strap comprising an elongated body portion provided 50 with an elongated flat surface to extend along the edge of the lens, a pair of ears secured to said body midway between its ends and extending

over the opposite faces of the lens and pivotally secured thereto, and a spring located between and symmetrical with respect to said ears and interposed between the flat surface of said body and the edge of the lens to rock along said flat surface as the lens and strap are moved about said pivot. 5

2. In an ophthalmic mounting, a lens strap comprising an elongated body portion provided with an elongated flat surface to extend along the 10 edge of the lens, a pair of ears secured to said body midway between its ends and extending over the opposite faces of the lens and pivotally secured thereto, and a leaf spring of concave shape located between said ears and interposed between the 15 flat surface of said body and the edge of the lens with its convex side adjacent said flat surface and its end portions against the lens to rock along said flat surface as the lens and strap are moved about said pivot. 20

3. In an ophthalmic mounting, a lens strap comprising an elongated body portion with an elongated flat surface to extend along the edge of the lens, a pair of ears secured to said body midway between its ends and extending over the 25 opposite faces of the lens and pivotally secured thereto, a spring located between and symmetrical with respect to said ears and interposed between the flat surface of said body and the edge of the lens to rock along said flat surface as the lens 30 and strap are moved about said pivot, and interengaging means on said spring and body comprising a recess in one and a projection on the other to fit therein.

4. In an ophthalmic mounting, a lens strap comprising an elongated body portion provided with an elongated flat surface to extend along the edge of the lens, a pair of ears secured to said body midway between its ends and extending over the opposite faces of the lens and pivotally secured thereto, a spring located between and symmetrical with respect to said ears and interposed between the flat surface of said body and the edge of the lens to rock along said flat surface as the lens and strap are moved about said pivot, and interengaging means on said spring and body comprising a recess in one and a projection on the other to fit therein, said pin being drawn up from and integral with the stock of the part on 45 which it is located. 50

JAMES A. SWEENEY.
